UNITED STATES PATENT OFFICE.

PATRICK J. KELLY, OF ELIZABETH, NEW JERSEY.

DIVIDING-HEAD FOR PUNCHING-MACHINES.

SPECIFICATION forming part of Letters Patent No. 642,822, dated February 6, 1900.

Application filed September 8, 1899. Serial No. 729,814. (No model.)

To all whom it may concern:

Be it known that I, PATRICK J. KELLY, a citizen of the United States, and a resident of Elizabeth, in the county of Union and State 5 of New Jersey, have invented a new and useful Improvement in Dividing-Heads for Punching-Machines, of which the following is a specification.

The object of my invention is to provide for 10 so presenting a boiler-head or other circular article to a punching-machine by which holes are to be punched and for so turning and otherwise changing the position of the said article relatively to the punch that the holes will 15 be spaced with positive precision in one or more circular series without the need of any preliminary laying out by hand, such as has hitherto been done by compasses.

I will first describe, with reference to the 20 accompanying drawings, a dividing-head embodying my invention and afterward point out its novelty by claims.

Figure 1 of the drawings represents an elevation, partly in section; Fig. 2, a horizontal section in the line 2 2 of Fig. 1; Fig. 3, a view, 25 taken at right angles to Fig. 1, of the lower part of the dividing-head; Fig. 4, a central vertical section corresponding with Fig. 3, taken at right angles thereto.

Similar letters and numerals of reference 30 designate corresponding parts in all the figures.

a is a hollow stand or carriage fitted to a slideway *b* in a stationary bed-plate *c* and capable of sliding therein in a direction to and fro in relation to any suitable punching machine or apparatus—for example, a punch *d* and die *e*, such as are shown in Fig. 1. This to-and-fro movement is provided for by a rack 35 and pinion *g* on the bed-plate and a pinion *h*, attached to the stand *a*, the said pinion being turned by a hand-wheel *i*. The stand *a* is represented as constructed with a removable upper part or cap *j*, in which and in the lower part 40 of the stand are provided guides *k* for a central upright shaft or column *h*, on the top of which is a clamp *l* for securing to it the article in which holes are to be punched, (represented in Fig. 1 as a boiler-head 10,) in the 45 turned-over margin of which holes are to be punched. The said shaft *h* is capable of turning and of moving lengthwise in its guides *k*.

The shaft *h* has in its lower part a series of grooves 12, which constitute a toothed rack and which while the said shaft is turned to any position remains in gear with a pinion *l* (see Fig. 2) on a horizontal shaft *m*, which works in bearings in the sides of the upper part *f* of the stand and which is furnished outside of the stand with a worm-gear 8, which 55 gears with an endless screw 9 on a shaft *n*, working in bearings in brackets *o* on the stand. The said shaft *n* is furnished with a hand-wheel or crank *p*, by the turning of which the shaft *h* is raised or lowered. To support the 60 shaft *h* in the position to which it is vertically adjusted, there is placed under its bottom within the stand *a* a sole-piece *q*, which is adjusted by a wedge *r*, which works through an opening in one side of the stand and is moved 65 by the turning of the hand-screw *s*, which screws into the said wedge and turns, but is confined lengthwise in a bracket *t*, which is fastened to the outside of the stand. For the 70 purpose of turning it the shaft or column *h* has provided on it a worm-gear *u*, which gears with an endless screw *v* on a shaft *w*, which 75 works in bearings in the sides of the stand.

To provide for the vertical movement of the shaft *h* without disturbing the engagement of the worm-gear *u* and endless screw *v*, the said gear is confined vertically between the upper and lower guides *g* and fitted with a spline which enters a groove 11 in the said shaft and permits the said shaft to slide 80 through the said gear, but compels the gear and shaft to turn together.

The shaft *w* has fast upon it, outside of the stand *a*, a slotted arm *x*, which carries a pin *y*, which is adjustable in the said arm toward and from the shaft *w* and capable of entering any one of the several circular series of equidistantly-spaced holes in an ordinary circular dividing-plate *z*, which is affixed to the exterior of the stand. The number of revolutions of the shaft *w* to one of the shafts *h* and the number of holes in each of the circular series of the dividing-plate being determined, it will be easy to determine to which of the circular series of holes in the dividing-plate to adjust the pin *y* and to determine how many revolutions or such fractional parts of a revolution as are represented by the 95 spaces between the holes of the series it may 100

be necessary to turn the arm *x* and the shaft *w* to turn the shaft *h* and the head 10 or article clamped thereto proper and accurate distances to present the said article accurately 5 to the punch for the punching of the holes all around the said articles at the desired uniform distances apart.

By the raising and lowering of the shaft *h* in the stand a provision is afforded for the 10 punching of two or more series of holes in the head or article 10. By the movement of the stand *a* in the slideway *b* of the bed-plate *c* provision is afforded for punching articles of various sizes.

15 The clamp for securing the boiler-head or other article 10 to the shaft *h* may be of any suitable kind. It is represented as consisting of a circular centering-block *i* of a size to fit a central hole in the said article secured 20 to the head of the shaft *h*, a clamping-cap *j*, which bears upon the said article around the said block, and a clamping-bolt *k*, attached to the centering-block and provided with a nut by which the said cap *j* is caused to hold 25 down the said article upon the head of the shaft *h*. If the boiler-head or other article to be punched should not normally require a central hole, such a hole of small size may be made in it for the purpose of receiving a centering-block or clamping-bolt and after the 30 punching has been done may be closed in any suitable manner.

It is obvious that I may apply my dividing-head as well to a drilling-machine as to a 35 punching-machine, and therefore I consider such application as within the scope of my invention.

What I claim as my invention is—

1. In a dividing-head for a punching-machine having a horizontal punch, the combination of an upright shaft and a support therefor, means for attaching to said shaft an article to be punched, means for turning said shaft and means for moving said shaft 40 vertically in relation to said punch while in engagement with the means for turning it, substantially as herein described.

2. In a dividing-head for a punching-machine having a horizontal punch, the combination of an upright shaft and a support therefor, means for attaching to said shaft an article to be punched, means for turning said shaft, means for moving said shaft 45 vertically in relation to said punch while in engagement with the means for turning it, substantially as herein described.

tically in relation to said punch while in engagement with the means for turning it, a 55 dividing-plate affixed to said support, a second shaft geared with said upright shaft and a pin carried by said second shaft and adjustable at different distances from the center thereof engaging with said dividing-plate, 60 substantially as herein described.

3. In a dividing-head for a punching-machine having a horizontal punch, the combination of an upright shaft and a stand therefor, a bed-plate in which said stand is supported, means for moving said stand on the bed-plate, means for securing to said shaft an article to be punched, means for turning said shaft, and means for moving said shaft vertically in relation to said punch while in 70 engagement with the means for turning it, substantially as herein described.

4. In a dividing-head for a punching-machine, the combination of a shaft and a support therefor, means for securing to said 75 shaft an article to be punched, a worm-gear fitted to said shaft to turn with it but confined in the direction of the length of the said shaft, an endless screw and means for turning the same in engagement with said 80 worm-gear for turning the shaft, a rack encircling said shaft, and a pinion and means for turning the same in engagement with said rack for raising and lowering the shaft, all substantially as herein set forth. 85

5. In a dividing-head for a punching-machine, the combination of an upright shaft and a stand therefor, means for attaching to said shaft an article to be punched, a toothed rack encircling said shaft, a pinion and means 90 for turning the same in engagement with said rack for raising and lowering said shaft, a sole-piece in said stand under said shaft, a wedge under said sole-piece and a screw for operating the said wedge for the adjustment 95 of the sole-piece, all substantially as herein set forth.

In testimony that I claim the foregoing as my invention I have signed my name, in presence of two witnesses, this 25th day of August, 1899.

PATRICK J. KELLY.
